UNITED STATES PATENT OFFICE

130,995

DESIGN FOR A DISPLAY CASE

Adolph T. Mayer, Los Angeles, Calif., assignor of one-half to Donald L. Hesse, Los Angeles, Calif.

Application October 21, 1940, Serial No. 95,957

Term of patent 3½ years

To all whom it may concern:

Be it known that I, Adolph T. Mayer, a citizen of the United States, residing at Los Angeles, in the county of Los Angeles and State of California, have invented a new, original, and ornamental Design for Display Cases, of which the following is a specification, reference being had to the accompanying drawing, forming part thereof.

Fig. 1 is a front perspective view of a display case, showing my new design.

Fig. 2 is a rear elevational view thereof, on a reduced scale.

Fig. 3 is a top plan view.

I claim:

The ornamental design for a display case, as shown.

ADOLPH T. MAYER.
